DOWEL HOLE DRILLING JIG

James L. Cleveland, 351 Clyde Ave., Calumet City, Ill.
Filed June 28, 1960, Ser. No. 39,330
5 Claims. (Cl. 77—62)

This invention relates to a jig for drilling dowel holes in pieces of lumber. It is primarily intended for drilling dowel holes in the edges of window sash and doors but it is also applicable to other pieces of lumber of comparable thickness and to cabinet work generally.

The object of the invention is to provide a jig for drilling two parallel dowel holes at a predetermined distance apart.

Another object of the present invention is to provide a jig for drilling dowel holes which is adjustable in two planes to space the holes along the edge of a piece of lumber from both the end and with respect to the thickness of the piece of lumber.

A further object of the present invention is to provide a jig for drilling dowel holes which has a wide range of adjustment with respect to the end of the piece of lumber in which the holes are being drilled, so that it may be used for drilling holes in the edge of a door or window sash adjacent the end of the latter for dowels, and also in the edge of the door or window sash at a considerable distance from the end of the latter for hinges or latches.

Still other objects, advantages and improvements will become apparent from the following specification, taken in connection with the accompanying drawings, in which:

FIGURE 1 is a top plan view of the drilling jig according to the present invention.

FIG. 2 is an end elevational view of the drilling jig.

FIG. 3 is a longitudinal vertical sectional view, taken on the section line 3—3 of FIG. 1 and looking in the direction of the arrows.

FIG. 4 is a transverse vertical sectional view, taken on the section line 4—4 of FIG. 3 and looking in the direction of the arrows.

FIG. 5 is a detail end elevational view showing the stop plate, which is used when drilling holes in the edge of a window sash or door close to the end of the latter.

FIG. 6 is a similar view of the elongated stop bar, which is used for drilling holes in the edge of a window or door at a considerable distance from the end of the latter.

FIG. 7 is a detail sectional view, taken on the section line 7—7 of FIG. 6 and looking in the direction of the arrows, showing the attachment of the elongated drilling bar to the frame of the drilling jig.

FIG. 8 is a detail sectional view, taken on the section line 8—8 of FIG. 3 and looking in the direction of the arrows, showing the mounting of one of the vertically adjustable blocks on one of the longitudinally adjustable slides.

FIG. 9 is a detail isometric view of one of the vertically adjustable blocks.

FIG. 10 is a detail isometric view of one of the longitudinally adjustable slides.

FIG. 11 is a detail isometric view of the thrust block.

Referring now to the drawings in detail and to FIGS. 1, 2 and 4 in particular, the piece of lumber, such as the edge of a window sash or door in which holes are to be drilled, is shown at A. The drilling jig according to the present invention, includes a frame comprised in part by a rectangular vertically positioned plate 10. This plate 10 has two rectangular apertures 10a and 10c therein, which are positioned with their longer sides parallel to and symmetrically disposed with respect to the longitudinal center line of the plate and are separated by a web 10b along the transverse center line. At its top the plate 10 has an integral upper right angle flange 11, which is preferably curved in the arc of a circle in top plan view. The drill-

2

ing jig is in part secured to the piece of lumber A by a power screw 14, which is mounted in a suitable screw threaded hole in the upper horizontal flange 11. At its upper end the screw 14 has a rod 15 positioned in a diametrically located hole therein and this rod has enlarged ends 15a—15a to hold same in place. It will be obvious that by turning the rod 15 the screw 14 may be rotated in the proper direction. The lower end of the screw 14 is of inverted frusto-conical shape at 14a and this lower end is slidably received in a dove-tailed slot 16a in a thrust block 16. The thrust block 16 is adapted to rest on one surface of the piece of lumber A.

At its bottom the plate 10 is formed with a second horizontal flange 12, which is positioned on the same side of the plate and is parallel relationship to the upper horizontal flange 11. This lower flange 12 also has two rectangular apertures 12a and 12c therein, the side walls of which each have a 1° longitudinal taper. The flange is positioned with the rectangular apertures 12a and 12c having their tapered sides parallel to and symmetrically disposed with respect to the longitudinal center line of the flange and are separated by a web 12b, which is positioned along the transverse center line of the flange. A suitable scale 12d is scribed on the top surface of the flange 12 between the rectangular apertures 12a and 12c and the outer edge of the flange. This flange 12 is adapted to be positioned on the outer side of the piece of lumber A, with the scale 12d projecting beyond the end of the latter.

A stop plate 17 is provided for determining the position of the drilling jig along the edge of the window sash or door A, when the jig is being used for drilling dowel holes close to the end of the latter. This stop plate has an elongated slot 17a along its longitudinal center line and a right angle flange 17b at its outer end to facilitate gripping. A screw 18 is positioned in the elongated slot 17a in the stop plate and is received in a suitable screw threaded hole in the vertically positioned plate 10. The inner end of the stop plate abuts the end of the door or window sash A to position the drilling jig at some location determined by alignment of a selected mark on the scale 12d with the end of the door or window sash A.

For drilling holes in the edge of a door or window sash A a greater distance from the end of the latter, that is when hinges or latches are to be mounted in the edge of the door or window sash, an elongated scale bar 19, as shown in FIG. 6, is provided. This scale bar has an elongated slot 19a, positioned symmetrically with respect to the longitudinal center line, and a scale 19b scribed on one face between the slot 19a and one side. As shown in FIG. 7, this scale is adapted to be received in a slot 50 10d in the plate 10, which slot is positioned symmetrically with respect to the hole which receives the screw 18. At the inner end of the scale 19 there is a slot 19c, which is aligned longitudinally with the slot 19a and receives the screw 18, and the inner end is formed with right angle fingers 19d, which engage one edge of the vertically positioned plate 10. A bolt 20 is movable along the elongated slot 19a and this bolt has a square bottom 20a and a cylindrical knurled nut 20b. By setting the bolt 20 with its transverse diameter in alignment with a selected mark on the scale 19b, and one side of the bottom 20a of the bolt abutting the end of the door or window sash A, the vertically positioned plate 10 may be set at a desired location along the edge of the door or window sash within the limits of the slot 19a in the scale.

The vertically positioned plate 10 is also formed at its bottom with a third flange 13, which is horizontally aligned with the second flange 12, but on the opposite side of the plate from the latter. This latter flange has two rectangular apertures 13a and 13c therein, the side walls of which each has a 1° longitudinal taper. The flange is positioned with the rectangular apertures 13a

and 13c having their tapered sides parallel to and symmetrically disposed with respect to the longitudinal center line and are separated by a web 13b, which is positioned along the transverse center line of the flange. A suitable scale 13d is scribed on the top surface of the flange between the apertures 13a and 13c and the outer side of the flange.

Vertically positioned slides 21-21 are movable along the apertures 13a and 13c in the flange 13. As shown in FIG. 8, these slides are comprised by a base and parallel legs 21a-21a, with one of the legs having a scale 21b scribed thereon. The corners of the base are cut away and the base is cut away on its transverse center line to form parallel lugs 21c-21c, which latter are undercut on their side walls at 21d-21d. Also, the inner side walls of the lugs 21c-21c are tapered at approximately 1°. The slides 21-21 are mounted in vertical position on the flange 13, with the lugs 21c-21c being received in the respective apertures 13a and 13c. Short flat headed bolts 22 have their heads received in the slots 21d-21d in the bases of the slides 21-21. Clamping plates 23 have their opposite corners cut away, for receiving the corners of the apertures 13a and 13c in the flange 13, and have central holes therein for freely receiving the bolts 22. Wing nuts 24 are received on the outer ends of the bolts 22 and serve to hold the slides 21-21 against the upper face of the flange 13.

The combination of the 1° longitudinal taper on the side walls of the rectangular apertures 12a and 12c in the flange 12, or the 1° longitudinal taper on the side walls of the rectangular apertures 13a and 13c in the flange 13, with the 1° taper on the inner side walls of the lugs 21c-21c on the slides 21-21, provides for more easy movement of the slides, after the wing nuts 24-24 have been loosened; also, that when the slides 21-21 have been re-set and the wing nuts 24-24 tightened, the slides will line up better and be positioned at 90° to the flange 13.

As shown in FIGS. 2, 3 and 9, vertically slidable blocks 25-25 are provided for mounting drill guides 29-29. These slidable blocks have their corners cut away along the height on their inner faces and the blocks are also cut away along their transverse center lines to form parallel lugs 25a-25a, which lugs are undercut along their side walls at 25b-25b. In one side wall of each block there are formed inverted V shaped notches 25c and slots 25d are formed in the outer end faces, which slots intersect the notches 25c. The slide blocks 25-25 are positioned on the inner faces of the lugs 21a-21a of the slides 21-21, respectively, with the lugs 25a-25a, between the legs 21a-21a of the latter. Short flat headed bolts 26-26 have their heads received in the slots 25b-25b of the clamping blocks 25-25. Clamping plates 27-27, similar to the previously described clamping plates 23, are placed over the outer faces of the legs 21a-21a of the slides 21-21, with the cut away corners on the clamping plates receiving the corners of the legs, and the bolts 26-26 pass freely through central holes in the clamping plates. Wing nuts 28-28 are received on the outer ends of the bolts 26-26 and serve to hold the slide blocks 25-25 against the inner faces and the clamping plates 27-27 against the outer faces of the parallel legs 21a-21a of the vertically positioned slides 21-21.

A pair of guide tubes 29-29 is provided and these tubes serve to direct the drills against the edge of the door or window sash. These tubes are held in place by eye bolts 30-30, which are opened by having their free ends spread apart from their shanks over the arc of approximately 120°. The shanks of the eye bolts 30 are positioned in the slots 25d in the slide blocks 25 and received wing nuts 31-31 on their outer threaded ends, which nuts abut the top faces of the blocks. The eye bolts 30-30 hold the guide tubes in place against one side of the V shaped notches 25d-25d in the slideable blocks

25-25 by thrust exerted diametrically of the eyes and across the chords of the open sections of the latter.

In use, let it be assumed that parallel holes are to be drilled in the edge of a door or window sash A adjacent the end of the latter for driving in dowels to hold longitudinally and transversely positioned members of the door or window frames together. The screw 18 is loosened so as to leave the stop plate 17 freely slideable. The plate 10 is positioned against the edge of the door or window sash A. The transverse center line between the two holes is determined by setting a preselected mark on the scale 12d on the flange 12 in alignment with the end of the door or window sash A. The stop plate 17 is then shoved inwardly against the edge of the door or window sash and the screw 18 tightened. This fixes the spacing of the two holes to be drilled with respect to the end of the door or window sash A. If a number of doors or window sash are to have pairs of holes drilled in their edges at the same distance from their ends, the setting of the stop plate 17 will remain unchanged throughout the drilling operation. The power screw 14 is now turned to grip the door or window sash A between the thrust block 16 and the lower flange 12.

Where holes are to be drilled in the edge of the door or window sash A at some distance from the end of the latter, as where hinges or latches are to be placed on the edge of the door or window sash, the slides 21-21 carrying the guide tubes 29-29 are removed from the elongated rectangular apertures 13a and 13c in the flange 13 and are inserted in the elongated rectangular apertures 12a and 12c in the flange 12. The flange 13 is then positioned under the window sash or door A, replacing the flange 12. The power screw 14 and the thrust block 16 are not used in this drilling operation. The elongated scale bar 18 is inserted in the slot 104, with the fingers 19d-19d on the scale bar against the inner edge of the frame 10. The spacing of the holes to be drilled from the end of the door or window sash S is determined by the scale 19b on the elongated bar and the bolt 20 set in position in the elongated slot 19a in the scale bar with one face of the square head 20a abutting the end of the door or window sash A. In this use of the drilling jig, it will be inverted from the previous position with the lower flange 12 against the upper face of the door or window sash A and the thrust block 16 against the under face.

The spacings of the holes to be drilled with respect to the transverse center line are now determined by loosening the wing nuts 24-24 and moving either or both of the vertically positioned slides 21-21 towards or away from the transverse center line, and then tightening the wing nuts. The settings of these slides are determined by the marks on the scale 13d on the flange 13.

Similarly, the spacings of the holes to be drilled with respect to the longitudinal center line of the edge of the door or window sash A are determined by loosening the wing nuts 28 and moving the slide blocks 25-25 upward or downward along the vertically positioned slides 21-21 and then tightening the wing nuts. The settings of these slide blocks are determined by the marks on the scale 21b on the slides.

Having now fully described my invention, what I claim as new and useful and desire to secure by Letters Patent of the United States is:

1. A drilling jig including a plate having parallel upper and lower flanges on one side and a lower flange on the other side, a power screw mounted in a hole in the upper flange for engaging a piece of lumber to be drilled against the first lower flange, a slide member mounted for movement along said second lower flange, a block mounted for movement along said slide member, and a drilling guide carried by said block.

2. A drilling jig including a plate having parallel upper and lower flanges on one side and a lower flange on the other side with an elongated aperture therein, a

5

power screw mounted in a hole in the upper flange for engaging a piece of lumber to be drilled against the first lower flange, a slide member mounted for movement along said second lower flange and having lugs thereon received within the elongated aperture in the latter, a block mounted for movement along said slide member, and a drilling guide carried by said block.

3. A drilling jig including a plate having parallel upper and lower flanges on one side and a lower flange on the other side, a power screw mounted in a hole in the upper flange for engaging a piece of lumber to be drilled against the first lower flange, a pair of slide members mounted for movement along said second lower flange, blocks mounted for movement along said slide members, and drilling guides carried by said blocks.

4. A drilling jig including a plate having parallel upper and lower flanges on one side and a lower flange on the other side with a pair of elongated apertures therein, a power screw mounted in a hole in the upper flange for engaging a piece of lumber to be drilled against the first lower flange, a pair of slide members mounted for movement along said second lower flange and having lugs thereon received within the apertures in the latter, blocks mounted for movement along said slide members, and drilling guides carried by said blocks.

5. A drilling jig including a plate having parallel upper and lower flanges on one side and a lower flange on the other side with a pair of elongated apertures therein, a power screw mounted in a hole in the first upper flange for engaging a piece of lumber to be drilled against the first lower flange, a pair of parallel legs and a pair of lugs thereon with slots formed complementally in said lugs, said lugs being received within the elongated apertures in the second lower flange, bolts mounted in said slots in the lugs and projecting through the apertures, clamping plates surrounding said bolts, nuts on said bolts engaging said clamping plates, slidable blocks mounted between the legs of said slide members and having slots in one face, bolts mounted in the slots in said slidable blocks and projecting between the legs, clamping plates surrounding said bolts, nuts on said letter bolts engaging said letter clamping plates, eye bolts secured to said slidable blocks, and guide tubes carried by said eye bolts.
